UNITED STATES PATENT OFFICE.

HARRY JAMES YATES, OF ASTON, BIRMINGHAM, ENGLAND.

GAS-FIRE.

1,183,617.

Specification of Letters Patent. Patented May 16, 1916.

Application filed July 29, 1914. Serial No. 853,977.

To all whom it may concern:

Be it known that I, HARRY JAMES YATES, subject of the King of Great Britain, residing at Essex Works, Thimble Mill Lane, 5 Aston, in the city of Birmingham, England, managing director of company, have invented certain new and useful Improvements Relating to Gas-Fires, of which the following is a specification.

10 This invention relates to gas fires of the type comprising a number of radiants or heating elements placed in conjunction with a fire-brick back and the nozzles of a gas burner.

15 In well designed gas fires no difficulty is experienced in withdrawing all the products of combustion from the fire to the chimney and effectively preventing escape of any such products into the room. The 20 size of the orifice required for proper conveyance of the combustion products to the chimney is, however, limited, and in consequence while a well designed gas fire does not contaminate the air of a room it may 25 sometimes impair the ventilation of a room where such ventilation is made to depend chiefly upon the air which will pass through the outlet orifice of the gas fire.

20 The object of this invention is to enable such gas fires to be employed not only for heating purposes without contaminating the atmosphere of a room, but also to produce a more ample ventilation than has been possible with gas fires hitherto.

25 The invention comprises the provision in a gas fire as above described, of a pair of outlet apertures from the fire to the chimney, one arranged in a suitable position and of suitable dimensions for the passage of 30 the combustion products and the other so dimensioned and positioned as to allow of a flow of air caused by the heated products of combustion.

35 In the two accompanying sheets of explanatory drawings:—Figures 1, 2, 3 and 4 are vertical sections of four different gas fires constructed in accordance with this invention. Fig. 5 is a front elevation broken away to show the burner of the 40 form shown in Fig. 1. The front elevation of each of the fires shown in Figs. 2, 3 and 4 is substantially the same as that shown in Fig. 5.

45 In the construction of a gas fire as shown in Fig. 1, the fire-brick back *a*, along the lower part of the face of which the usual

vertical heating elements *b* are arranged (with horizontal elements *c* when such are employed), is constructed, either from one piece or a number of suitably shaped separate pieces, to provide a comparatively narrow opening *d* extending across the front of the grate immediately above the top of the heating elements. This opening forms the passage for the combustion products, and is inclined upward and communicates with the chimney *e*. Under the usual canopy *f* of the gas fire another and usually larger opening *g* is provided. This opening constitutes the passage for air and also 55 communicates with the chimney *e*. The two passages may be so shaped and arranged as to form a pair of complementary nozzles enabling the rapid flow of a comparatively small quantity of combustion 60 products through the one to induce a slower but larger flow of air through the other.

While the passage *d* is properly proportioned to deal with the combustion products and is placed relatively to the radiants and 65 fire-brick back in the best position for withdrawing the products to the chimney and preventing escape into the room, the passage *g* is situated sufficiently far from the radiants to avoid any serious cooling effect 70 upon the fire by the air flowing into that passage.

75 By the provision of two passages for the combustion products and air as above described it is found that without loss of efficiency a gas fire can be utilized for promoting greater ventilation of a room than when provided with a single passage designed mainly for insuring proper withdrawal of 80 the combustion products.

85 The invention is not limited in such gas fires to any particular number, shape, disposition or construction of the passages for air and combustion products, as these details 90 may be varied to meet different requirements. In Fig. 2, for example, a modified construction is shown which is distinguished from that above described mainly by the addition of an intermediate passage *h* which 95 may be regarded as part of either the main gas burnt passage or of the main air passage. The said passage *h* conveys not only air to the chimney but also any residue of combustion gases which may escape the passage *d* and pass over the upper face *a'* of the 100 fire-brick *a*. The greater part of the air stream flows through the passage *g*. Fig. 3

- is similar to Fig. 2 excepting in the shape and disposition of the passages *d*, *g* and *h*. The construction shown in Fig. 4 is characterized by the disposition of the passage *d*.
5 This is situated rather higher above the radiants than in the other constructions described, and may receive part of the ventilating air in addition to the products of combustion. The remainder of the air is drawn beneath the canopy into the passage *g* where it is sufficiently removed from the radiants to avoid any detrimental cooling effect upon the radiants.
10 The heating elements *b* consist of skeleton or perforated tubes of refractory material each of which is situated over a nozzle of the burner *h*. A flame from a nozzle passes into the interior of each tube and raises the latter to a state of incandescence.
15 20 The burnt gases escaping through the open sides of the tubes pass along the front faces of the fire-brick back and enter the outlet passage *d*. The pieces *c* are of similar material to the pieces *b* and are also made in an open or skeleton tubular form. These are heated by the hot gases passing away at the tops of the elements *b*. The heating elements *b* and the pieces *c* form no part of the invention, being old and well known.
25 30 Having thus described my invention what I claim as new and desire to secure by Letters Patent is:—
1. In gas fires provided with heating elements and in which the ventilation of the room containing the fire is chiefly dependent upon the air which will pass through the outlet from the gas fire to the chimney, the

combination with a gas fire, of a pair of outlet passages communicating with and permanently open to the chimney, one arranged adjacent to the heating elements of the gas fire for the conduction of combustion products to the chimney, and the other above and at a distance from the said heating elements for the conduction to the chimney of a flow of air produced by the combustion products, the two passages opening adjacent to each other on the chimney side, substantially as described. 40 45

2. In gas fires provided with heating elements and in which the ventilation of the room containing the fire is chiefly dependent upon the air which will pass through the outlet from the gas fire to the chimney, the combination with a gas fire, of a pair of outlet passages communicating with and permanently open to the chimney, one arranged adjacent to the heating elements for the passage of combustion products and the other above and at a distance from the heating elements for the flow of air produced by the combustion products, and an additional passage between the said passages for air and combustion products, all the passages opening adjacent to each other on the chimney 50 55 60 65 side, substantially as described.

In testimony whereof I have signed my name to this specification in the presence of two subscribing witnesses.

HARRY JAMES YATES.
